UNITED STATES PATENT OFFICE.

ROSCOE BEAN, OF BEREAL, OHIO.

VALVE-REFACING TOOL.

1,359,316.

Specification of Letters Patent. Patented Nov. 16, 1920.

Application filed August 18, 1919. Serial No. 318,123.

To all whom it may concern:

Be it known that I, ROSCOE BEAN, a citizen of the United States, residing at Berea, in the county of Cuyahoga and State of 5 Ohio, have invented certain new and useful Improvements in Valve-Refacing Tools, of which the following is a specification.

My invention relates to improvements in valve refacing tools, and more particularly 10 to that class or type which are designed to reface the heads of gas engine valves commonly known as "puppet" valves.

The primary object of the invention is the provision of a generally improved tool of 15 this class which will be exceedingly simple in construction, cheap of manufacture and efficient in use.

A further object is the provision of an improved tool of this class in which improved valve and valve cutter carrying members are provided so arranged and disposed relative to each other as to hold and carry the rotating valve stem and valve head in proper position to the improved 20 cutter so that the face cut upon the periphery of the valve head will be at a proper angle to the common axial plane of the valve stem.

A still further object is the provision of 25 an improved multiple faced cutter having its cutting faces extending at right angles to each other and so arranged and positioned with respect to the stem carrying bearings and the head of the valve as to be interchangeable in the tool carrying or cutter carrying member so as to provide eight cutting edges, the improved cutter being also so mounted as to be firmly held in proper angular relation to the revolving valve head and 30 at the same time provide ample clearance for the cutting edges of the cutter.

A still further object of the invention is the provision of improved adjustable bearings adapted to removably receive and contain 35 the valve stem of the valve to be treated, and having improved means for adjusting such bearings to conform to the particular valve stem and hold the same together with the cutter head in proper position while being rotated in the valve head cutting or refacing operation.

A still further and very important object 40 of the invention is the provision of an improved coiled tension spring mounted at one 45 side of the valve stem receiving bearings adapted to removably receive and contain

the valve stem, said stem being provided with an improved combined spring tension adjusting device and valve stem rotating or operating handle.

With the above mentioned and other ends in view the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1, is a front elevation of a tool constructed in accordance with this invention, the valve to be operated upon being shown in dotted lines and the combined operating handle and tension device being shown partly in section for the purpose of clearer illustration of the 75 parts.

Fig. 2, an end view partly in section taken on line 2—2 of Fig. 1.

Fig. 3, a cross sectional view taken on line 3—3 of Fig. 1.

Fig. 4, a perspective view of the improved multiple faced cutter tool detached.

Similar numerals of reference designate like parts throughout all the figures of the drawings.

The improved tool comprises a suitable frame 1, provided with spaced bearing members 1^a, to removably receive and contain the stem 2, of the valve to be treated or refaced.

As a convenient means of holding the frame and the valve while being operated upon either by a hand or by a vise or other convenient means of support, the frame 1, is preferably provided with a handle 1^b, and as a means of providing adjustable bearings 1^a, to compensate for wear and also to adapt the same to stems of somewhat varying size and provide a close fit during the valve grinding operation the upper ends of the 100 bearings 1^a, are preferably split, as at 1^c, and provided with adjusting screws 1^b, as shown.

As a means of properly holding and supporting the cutter hereinafter referred to 105 relatively to the beveled edge or face 2^a, of the valve head 2^b, and as a means of presenting the cutting edge of the tool at the proper angle to the common axial plane of the stem 2, (usually at an angle of about 45 degrees) 110 the frame 1, is provided with a tool cutter carrying member 1^d, having its common or

axial plane extending at an angle of approximately 45 degrees to the axial plane of the stem 2, and the common axial plane of the bearings 1^a, and the plane of rotation 5 of the valve head 2^b, and as a means of transforming one edge of the face of the cutter into a cutting edge and affording ample clearance, the tool or cutter carrying member 1^c, is off-set to one side of the plane passing 10 through the axial plane or common center of the stem 2, and head 2^b, as will clearly appear upon reference to Fig. 2, of the drawings.

As a means of interchangeably receiving 15 the improved cutter so as to utilize all of its various cutting faces and also supporting the same in proper position, the cutter carrying member 1^c, is provided with a cutter receiving recess providing parallel extending 20 sides or shoulders 1^d, adapted to receive and abut against the opposite parallel extending face sides of the cutter.

The improved cutter 3, is provided with a plurality of cutter faces 3^a, extending at 25 right angles to each other and arranged uniformly at right angles to the face sides of the cutter 3, so that when the latter is mounted in the off-set cutter carrying member 1^c, the edge of the face 3^a, will form a cutting 30 edge with respect to the beveled portion of the valve head 2^b, being treated and thus the cutter faces 3^a, present opposite cutting edges so that when the edges on one side become dull the plate or cutter 3, may be reversed and the opposite edges be used, thereby providing for eight cutting edges 35 where the cutter is provided with four sides, as shown.

As a means of securing the cutter 3, in 40 place, the latter is provided with a central fastening opening 3^b, adapted to receive and contain a suitable fastening and clamping element, in the present instance, in the form of a threaded screw 4, passing through the 45 same and through a suitable opening in the cutter carrying member 1^c, and secured and clamped on the opposite side by means of a nut 4^a.

As a means of providing for the proper 50 tension upon the valve head as the latter is revolved through the medium of the valve stem 2, one side of the frame is provided with a coiled tension spring 5, having one end secured in a suitable opening in one of 55 the bearing members 1^a, said spring extending in substantially the same axial plane with the plane of the bearing openings 1^a, and being of proper size to receive and contain the end of the valve stem 2, and as a 60 means of adjusting the tension of the spring 5, and also rotating the stem 2, the outer end of the latter is provided with a combined spring tension adjusting device and handle 6, the head of the handle 6, being adjustably secured on the stem 2, by means of a

suitable adjusting element 6^a, in the present instance, in the specific form of a set screw. It will thus be seen that the handle and spring tension adjusting device 6, may be readily attached to the valve stem and that 70 the tension of the valve head upon the adjustable cutters 3, may be readily regulated.

From the foregoing description, taken in connection with the accompanying drawings, the operation and advantages of my 75 invention will be readily understood.

Having thus described one of the embodiments of my invention, what I claim and desire to secure by Letters Patent, is,—

1. In a valve refacing tool, the combination 80 with a handled frame provided with bearings adapted to receive the stem of the valve and provided with a cutter and cutter carrying member, a relatively fixed coiled tension spring carried by and attached to 85 said frame at one side adapted to receive the valve stem, and a combined spring tension adjusting device and handle adjustably secured to said stem and abutting against 90 said spring.

2. In a valve refacing tool, the combination 95 with a frame provided with spaced bearings to receive a valve stem; of a tool carrying arm extending to one side thereof at an angle of 45 degrees from the axial plane of said bearings and provided with a cutter receiving recess having its sides extending at right angles to the common longitudinal plane of said tool carrying member, and a reversible cutter tool having parallel sides and provided with four faces extending at right angles to each other and said parallel sides and fitted in said tool receiving recess.

3. In combination with the frame of a 105 valve refacing tool provided with bearings to receive the stem of the valve to be refaced, and a cutter carrying member extending from the common axial plane of said valve stem receiving bearings; of a multiple 110 faced reversible cutter on said cutter carrying member having its cutting edges arranged to extend at an angle to said axial plane and off-set to one side thereof and to the side opposite the direction of rotation 115 of said valve stem when inserted in said bearings, whereby the cutting face forms its own clearance at the rear of the cutting edge and relative to the edge of the valve being refaced so that all cutting faces may be used. 120

4. In a valve refacing tool, the combination 125 of a frame provided with bearing means to receive and carry the stem of the valve to be refaced, and a tool carrying arm extending therefrom, and a two-faced reversible cutting tool having a plurality of cutting edges inclined at an angle to the axial plane of rotation of said valve and to the side opposite the direction of rotation, whereby each cutting edge forms its own clearance 130

with the face of the valve being refaced so that all edges may be utilized.

5. In a tool for refacing valve parts, a multiple faced cutter each face of which has 5 a plurality of cutting edges, a cutter carrier provided with a guide to hold the valve parts and the cutter in proper relative operative relation, and fastening and locating 10 elements on said cutter carrier for positively locating and securing said cutter in predetermined positions with any one of its

faces located so that any one of its edges may form an active cutting edge inclined at an angle to the axis of the valve parts with its other or opposed face extending from 15 said active cutting edge arranged to form its own clearance whereby all of the cutting edges formed by the faces of the cutter may be utilized.

In testimony whereof I have affixed my 20 signature.

ROSCOE BEAN.
